HIGH-FREQUENCY DISCHARGE DEVICE

Laszlo U. Hamvas, Schenectady, N. Y., assignor
to General Electric Company, a corporation of
New York

Application June 27, 1951, Serial No. 233,798

7 Claims. (Cl. 313—158)

1

My invention relates to high frequency discharge device and more particularly to improved discharge devices of the magnetron type.

In certain applications of compact, relatively inexpensive electronic equipment, there is need for a generator of ultra high frequency electrical signals, for example, as in ultra high frequency television receivers or in small ultra high frequency communication transmitters and receivers. The frequency range of the electrical signals required in such applications includes frequencies of such magnitudes as to be unattainable in a practical sense from oscillators of the type used heretofore for generating cyclically varying electrical signals in compact, relatively inexpensive equipment used at lower frequencies. It has been known that electric discharge devices of the magnetron type will provide the necessary ultra high frequency electrical signals. However, magnetron devices which are presently known in the art, in general are, by their sizes, operating voltages, cost, and complexity, prohibited from use in a practical way as oscillating signal generators in applications of the type described.

It is a primary object of my invention to provide a new and improved electric discharge device of the magnetron type.

It is another object of my invention to provide an electric discharge device of the magnetron type which is of simplified and economical construction, easily produced on a low cost, mass production basis.

It is another object of my invention to provide an electric discharge device of the magnetron type which is suited in its simplified structure to be embodied in small sizes and mounted in conventional receiving tube envelopes.

It is still another object of my invention to provide such a magnetron device as described in the foregoing objects which may serve as a generator of ultra high frequency electrical signals such as are required from the local oscillator in an ultra high frequency television receiver or communication receiver.

In carrying out my invention in one form thereof, I provide an electric discharge device which includes an evacuated and hermetically sealed envelope within which there is mounted on two lead-in connectors, two anode members, each having a ring portion and a plurality of elongated elements or digital projections extending axially therefrom in a circular array and in mutually-spaced parallel relation. To each of the two ring portions, there is secured a disk of

insulating material having defined therein a central opening and a plurality of spaced slots around the opening. The ring portions with the disks secured thereto are mounted in spaced parallel planes with the digital projections from each ring portion interspaced between those from the other ring portion and extending for support into the slots in the disk secured to the other ring portion. Thus, all of the digital projections form a parallel mutually spaced circular array, alternate ones being supported from one ring portion and extending through slots in the insulating disk secured to the other ring portion. A tubular cathode member is conveniently mounted in centrally located relation within the circular array of digital projections, extending for insulated support through the central openings in the insulating disks. By this structure, the digital projections and the cathode member are easily and economically spaced accurately from one another and firmly supported so that such spacing is maintained.

Conventional means to heat the cathode member may be provided and connected to two of 25 the lead-in connectors; and the cathode member is also connected to a lead-in connector. A permanent magnet is provided around the exterior of the envelope and so oriented as to produce an axial magnetic field within the annular space 30 between the cathode member and the circular array of digital projections. Thus, when the two anode members are connected to an external resonant circuit and a direct current voltage applied between the cathode member and the anode 35 members, the radial electric field therebetween in conjunction with the axial magnetic field permits the device to produce ultra high frequency oscillating electrical signals in a manner of operation well-known in the art of magnetron discharge devices.

The novel features of my invention are pointed out with particularity in the appended claims. For a better understanding of the invention, however, together with further objects and advantages thereof, reference should be had to the following description taken in conjunction with the accompanying drawing, wherein the single figure is an enlarged perspective view of a magnetron discharge device embodying my invention.

In the drawing, I have shown an evacuated and hermetically sealed envelope 1, which preferably is generally cylindrical in shape, as shown. Envelope 1 includes a circular base portion 2, through which a plurality of electrically conductive and relatively stiff lead-in connectors

3—9 are sealed in mutually spaced and insulated relation. The connectors 3—9 may be conveniently arranged to cooperate with a conventional tube socket, such as is commonly used to support and electrically connect discharge devices, the arrangement shown in the drawing being suited for use with a 7 pin miniature type socket. For a purpose to become apparent hereinafter, envelope 1 is made of a non-magnetic material, either metal or glass. Base portion 2 is made of suitable insulating material, for instance either ceramic or glass, and sealed at its periphery to the main cylindrical portion of envelope 1. An exhaust and seal-off tubulation 10 may conveniently be located in the upper end of envelope 1 as shown.

Within envelope 1 and for practical purposes, entirely supported from connectors 6 and 7, there is provided an electrode structure including two anode members 11 and 12, a cathode member 13, and two disks 14 and 15 of insulating material. Supported from connector 4 so as to form an inductive loop, there is a strip 16 in which a suitable getter material, such as barium, is placed. After final evacuation and sealing of envelope 1, the loop may be excited with radio frequency energy to heat and vaporize the getter material which, as is well known, absorbs residual gases remaining in the envelope.

Directing particular attention now to the electrode structure of the illustrated device, it will be seen that anode members 11 and 12 include annular or ring portions 17 and 18 respectively which are supported in spaced parallel planes, i. e., in spaced coaxial relation, by welding or other fastening means, preferably from diametrically opposed connectors 6 and 7. A plurality of elongated anode elements or digital projections 19 extend axially from ring portion 17 in parallel mutually spaced relation; and a plurality of similar digital projections 20 extend in like manner from ring portion 18 in opposition to but interspaced between projections 19. Together, the plurality of digital projections 19—20 form a closed array of mutually spaced parallel extending elements which enclose a geometric space, preferably a cylindrical space formed by projections 19—20 in a circular array, coaxial with the mutual axis of ring portions 17 and 18.

Insulating disks 14 and 15 are mounted upon ring portions 17 and 18 as shown. A simple way to accomplish this mounting is provided by a plurality of tabs 21, spaced around the periphery of ring portions 17 and 18 intermediate the points from which digital projections 19 and 20 extend. Before final bending of tabs 21, they may be slipped through spaced slots 22 provided in disks 14 and 15; and a quick and simple bending of tabs 21 secures the disks to the anode ring portions as shown. Disks 14 and 15 are also each provided with a central opening 23 and a plurality of mutually spaced slots 24 around the opening therein. It will be obvious that a quick and economical stamping of sheet insulating material, preferably mica, for example, will provide the disks 14 and 15 with the openings 23, slots 22, and slots 24 therein.

Anode members 11 and 12 may also be formed by simple fabricating operations. Blanks in the form of a ring with alternate short spokes, to form tabs 21, and long spokes, to form digital projections 19 or 20, radiating from the peripheries thereof may be punched from sheet metal, preferably non-magnetic metal, as for instance stainless steel. The short spokes may

be bent in one direction to form tabs 21 and the long spokes bent 180 degrees in the other direction at their bases, and again 90 degrees at a point radially inward from the ring portions to provide projections 19 and 20, as shown.

When anode members 11 and 12 with disks 14 and 15 secured thereto are placed in spaced relation with digital projections 19 and 20, interspaced as shown, the free extremities of the digital projections 19—20 extend through slots 24 in disks 14 and 15. That is, alternate ones of the parallel mutually spaced projections 19—20 in circular array are supported between one anode ring portion and the insulating disk secured to the other ring portion. This arrangement is particularly advantageous because the spacings between alternate digital projections are thereby accurately effected along the whole length of the projections. Further, with digital projections 19—20 supported at both ends as shown, the original spacings are maintained even though the device be subjected to mechanical shocks or jars. The mutual spacings of digital projections 19—20 are accurately made and maintained; and the device, therefore, is not subject to microphonic or frequency drift disturbances during operation.

Tubular cathode member 13 is supported in insulated and accurately spaced relation within the array of digital projections 19—20 by disks 14 and 15, cathode member 13 extending between disks 14 and 15 through openings 23 as shown. This mounting arrangement for cathode member 13 has several advantages. First, since the size and location of openings 23 may be accurately determined when disks 14 and 15 are formed, cathode member 13 is accurately located within the array of digital projections 19—20; this is essential to good operation of the device. Second, cathode member 13 is not only electrically insulated from other components of the electrode structure, but is also thermally insulated since no metallic structure is in contact therewith to conduct heat away; this is an important feature because heating power for cathode member 13 during operation of the device is thereby minimized. Third, the structure and assembling thereof for mounting cathode member 13 are extremely simple and economical, being adapted for production on a mass production basis.

Coated upon the outer surface of cathode member 13, which may be made of nickel, is a thermionically emissive substance 25, for example, barium-strontium oxide, and mounted within cathode member 13 is a suitable heating element 26 which is connected to connectors 3 and 5 as shown to be supplied with heating current. The right end of cathode member 13, not visible in the drawing, is preferably closed by crimping or a suitable cap to reduce heat losses by radiation and is connected to connector 9 by means of a cathode tab 27. Also, as shown in the drawing, a convenient manner of mounting anode members 11 and 12 is to weld connectors 6 and 7 respectively to one of the tabs 21 thereon.

Suitable means, such as an annular permanent magnet 28 having diametrically opposed poles, are positioned externally around envelope 1 to provide an axial magnetic field in the annular space between digital projections 19—20 and cathode member 13. In order that the magnetic field strength, for a given magnet, in this space, be a maximum and virtually uniform, envelope 1

and anode members 11 and 12 should be of a non-magnetic material.

Although the operation of the magnetron device shown and described is conventional and well understood, it may be briefly described as follows: A direct current potential difference making anode members 11 and 12 positive with respect to cathode member 13 is applied between the anode members 11 and 12 and cathode member 13 through a circuit which, in combination with the section of transmission line formed by conductors 6 and 7, is resonant at a predetermined frequency. With this potential difference which creates a radial electric field, and with a suitable axial magnetic field, between digital projections 19-20 and cathode member 13, electrons emitted from the heated substance 25 move in curvilinear paths to set up oscillatory fields in the spaces between adjacent digital projections, which cause oscillatory electrical signals in the external resonant circuit. High frequency electrical energy may be extracted from the resonant circuit and the frequency of operation may be varied or tuned by changing the circuit parameters in the external circuit. It is understood that the capacitive reactance of the resonant circuit is provided, to a large extent, by the surfaces of closely spaced adjacent digital projections, while the inductive reactance is provided largely by the transmission line formed of connectors 6 and 7 and the external circuit connected thereto.

A notable feature of the present invention resides in the fact that the insulating disks 14 and 15 not only serve to securely support and position the extremities of digital projections 19-20 in mutually spaced and insulated relation, and to insulatably support cathode member 13 in accurately centered relation within digital projections 19-20, but also serve as end shields to prevent electrons from escaping axially out of the space between these members in which the forces of the electric and magnetic fields interact on the electrons. It is known that a considerable number of electrons tend to escape the interaction space if it is unclosed at its ends, thereby lowering the efficiency of operation. In the past, metallic end-shields have often been used at the ends of the interaction space to prevent electron escape; these shields were ordinarily maintained at cathode potential and necessarily were mounted in spaced or insulated relation with respect to the anode, thus adding complexity and cost to the devices in which they were employed. Also, the extra capacitance between the interdigital projections and the endshields was undesirable. In accordance with my invention, the insulating disks serve as end shields. The emitting substance 25 is not extended completely to the insulating disks 14 and 15, as shown in the drawing, so that electrons which do reach the disks do not possess enough velocity to cause damage to the disks or cause secondary emission therefrom. It is believed that disks 14 and 15 collect a few electrons, becoming negatively charged as a result, and then repel any additional electrons from leaving the interaction space and reaching the disks. If under extreme conditions, as for instance at excessively high anode voltages, however, it appears that electrons might strike disks 14 and 15 and cause damage thereto, flanges or embossments may be provided on cathode member 13 intermediate the ends of the emitting substance 25 and the disks to intercept electrons in their travel toward the disks.

In a preferred embodiment of my invention 75

illustrated by the drawing, the mutual axis of cathode member 13, ring portions 17 and 18, and the circular array of interdigital projections 19-20 is oriented at right angles to the major axis of envelope 1. Such an arrangement is preferred and advantageous for two reasons. First, the air gap across which magnetic flux must pass is minimized and a lower strength magnetic source, such as permanent magnet 28, may be employed to produce the same flux density in the interaction space than one needed for any other arrangement. Secondly, connectors 6 and 7 which form a transmission line to the external resonant circuit may be made extremely short and equal in length. If, for example, the electrode structure were positioned with the axis of cathode 13 vertical and the right-hand end thereof uppermost, connector 6 would necessarily be considerably greater in length than connector 7 and the transmission line formed by the connectors would be asymmetrical with respect to anode members 11 and 12 or else a terminal from the top of the envelope would be required.

From the foregoing, my invention is seen to be an electric discharge device of the magnetron type which is characterized by extreme simplicity and suited for mass production, even in small sizes. Through the use of insulating disks and the cooperating electrode structure shown and described the array of digital projections and the cathode member enclosed thereby are accurately spaced and firmly supported while all components of the structure are economical to fabricate and assemble. Furthermore, the device of my invention requires no end shields as are commonly known, since the insulating disks therein adequately serve also as end shields for the interaction space. This device has been built and tested in the illustrated embodiment and found to be very stable in its frequency of operation. It is also tunable, by varying the parameters of the external circuit, over a wide range of ultra high frequencies. The electrode structure is easily enclosed in an economical evacuated glass envelope and connected with connectors extending from the envelope to form a conventional pin-type base.

While the present invention has been described by reference to a particular embodiment thereof, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States is:

1. An electric discharge device comprising an hermetically sealed envelope, a plurality of elongated anode elements in parallel mutually spaced relation forming a closed array thereof, two anode ring portions mounted in spaced coaxial relation within said envelope, two disks of insulating material each secured to one of said ring portions, alternate ones of said anode elements being supported from one of said ring portions and the disk secured to the other ring portion, and a cathode member supported between said disks in accurately spaced relation within said array of said elements.

2. An electric discharge device comprising an evacuated envelope, two anode members supported in spaced relation within said envelope, each of said anode members having a ring portion and a plurality of mutually spaced parallel

elongated anode elements extending axially therefrom, two disks of insulating material each secured to one of said ring portions, said ring portions being positioned coaxially with the anode elements of each opposed and alternately interspaced with those of the other to form a circular array and extending for additional support through the disk secured to the other ring portion, and a cathode member accurately located and supported within said closed array of said anode elements by said disks.

3. An electric discharge device comprising an hermetically sealed evacuated envelope, a plurality of elongated anode elements mounted in circular array within said envelope and extending in parallel mutually spaced relation, two anode ring portions supported within said envelope in spaced coaxial relation, two disks of insulating material each secured to one of said ring portions, alternate ones of said anode elements being supported from one of said ring portions and extending for additional support through spaced slots defined in the disk secured to the opposite ring portion, said disks having a central opening defined therein, and a tubular cathode member extending in parallel centrally spaced relation within the circular array of said anode elements and through said openings and supported by said disks.

4. An electric discharge device of the magnetron type comprising an evacuated envelope, a plurality of lead-in connectors extending in sealed and mutually insulated relation from the interior to the exterior of said envelope, two anode members each having a ring portion and a plurality of parallel mutually spaced digital projections extending axially therefrom, said anode members each supported within said envelope from a different one of said lead-in connectors with the digital projections therefrom in opposed parallel interspaced relation, two disks of insulating material each secured to one of said ring portions, said disks having a plurality of spaced slots therein through which the extremities of the digital projections from the opposite anode member extend and having a central opening defined therein, and a cathode member extending between said central openings in said disks for insulated and centered support with respect to said interspaced digital projections.

5. An electric discharge device of the magnetron type, comprising a generally cylindrical hermetically-sealed, evacuated envelope including a base portion of insulating material, a plurality of lead-in connectors sealed in mutually insulated relation through said base portion, a plurality of parallel mutually spaced elongated anode elements in circular array, two anode ring portions supported in coaxial spaced relation with the mutual axis thereof perpendicular to the axis of said cylindrical envelope, two disks of insulating material each secured to one of said ring portions and having a central opening surrounded by a plurality of slots therein, alternate ones of said anode elements electrically and mechanically fastened to one of said ring portions and extending axially therefrom through the slots in the disk secured to the other of said ring portions, a tubular cathode member positioned coaxially with said ring portions and cen-

trally within said array of elements and extending through said spaced openings in said disks, a heating element within said tubular cathode member, and means for providing an axial magnetic field in the space between said cathode member and said array of anode elements.

6. An electric discharge device of the magnetron type comprising a generally cylindrical hermetically sealed evacuated glass envelope including a circular base portion, a plurality of lead-in connectors sealed with mutually insulated relation to said base portion, two anode members each having a ring portion and a plurality of parallel spaced digital projections extending axially therefrom, said ring portions being supported in coaxial spaced relation within said envelope one from each of two diametrically opposed lead-in connectors with the mutual axis of said ring members and with said digital projections oriented at right angles to the major axis of said envelope and with opposing digital projections mutually interspaced, two disks of insulating material each secured to one of said ring portions and having a central opening and a plurality of mutually spaced slots around said opening defined therein, the free extremity of each of said digital projections extending through one of said slots in said disks, a tubular cathode member extending through said openings in said disks for centrally spaced support with respect to said interspaced digital projections, and an annular permanent magnet having opposite poles diametrically opposed surrounding a portion of said envelope and oriented to provide an axial magnetic field in the space between said cathode member and said interspaced digital projections.

7. An electric discharge device of the magnetron type comprising an evacuated envelope, an insulating base portion forming a part of said envelope, a plurality of lead-in connectors sealed in said insulating portion and extending from the interior to the exterior of said envelope, two anode members each having a ring portion and a plurality of circularly spaced digital projections extending axially from said ring portion, said anode members being mounted within said envelope on a first and a second of said lead-in connectors respectively with the ring portions thereof in parallel spaced relation and the opposed digital projections thereof interspaced between one another intermediate the inner sides of said ring portions, two insulating disks each mounted on the outer side of one of said ring portions and having defined therein a central opening, and a tubular cathode member surrounded in spaced relation by said interspaced digital projections and extending between said insulating disks and through said central openings, said cathode member being connected to a third of said lead-in connectors.
